UNITED STATES PATENT OFFICE

2,597,714

CARBON FILAMENT HOLDER

Walter Fred Elsholz, Nampa, Idaho

Application January 25, 1951, Serial No. 207,714

10 Claims. (Cl. 314—1)

1

This invention comprises novel and useful improvements in arc lamps and more particularly pertains to improvements in positive carbon holder assemblies.

The present carbon holder assemblies in arc lamps utilize a single positive carbon holder, and when such lamps are used in conjunction with movie projectors, the practice is to utilize only positive carbons which are of sufficient length to permit showing of an entire reel without requiring replacement. Thus, the operators will remove and discard relatively short positive carbon rods when changing reels to permit uninterrupted showing of the reels.

An important object of this invention is to provide a positive carbon holder assembly which will permit successive burning of a plurality of carbons without an appreciable time delay or break in the continuity of the light between successive carbons, whereby relatively short carbons may also be utilized.

Another object of this invention is to provide a positive carbon holder assembly, in accordance with the foregoing object, with a mechanism for automatically effectuating the shift between one carbon rod and another carbon rod when the first rod has been consumed a predetermined amount, which mechanism will shift the consumed carbon out of operative position.

An important feature of this invention resides in the provision of a pair of carbon holders which are movable along the same path of travel and so constructed and arranged to support positive carbons in parallel relation to each other, with the carbon carried by one holder disposed rearwardly relative to the carbon carried by the other holder, together with a mechanism for shifting the carbon holders laterally of the path of travel thereof to move the consumed carbon out of registry with the negative carbon and shift the new carbon into registry therewith.

Another feature of this invention resides in the provision of a carbon holder assembly, in accordance with the foregoing feature, with a mechanism for automatically actuating the carbon holder shifting mechanism when the forward carbon has been consumed.

Yet another feature of this invention resides in the provision of a carbon holder assembly, in accordance with the foregoing features, with a common drive means for advancing both holders towards the negative carbon, together with a mechanism for automatically disconnecting the forward carbon holder from the drive means when that holder reaches a predetermined position relative to the negative carbon.

A further feature of this invention resides in the provision of a carbon guide for the carbon assembly constructed in accordance with the foregoing features, which carbon guide is shift-

2

able with the carbon holders to properly position the new carbon in registry with the negative arc lamp carbon.

Still a further feature of this invention resides in the provision of a carbon support carried by the forward carbon holder for guiding the carbon on the rearwardly disposed carbon holder.

These, together with various ancillary objects and features are attained by this device, a preferred embodiment of which has been illustrated in the accompanying drawings, wherein:

Figure 1 is a fragmentary side elevational view of the carbon holder assembly;

Figure 2 is a top plan view of the carbon holder assembly;

Figure 3 is a vertical sectional view taken on the plane 3—3 of Figure 2;

Figure 4 is a fragmentary transverse vertical sectional view, taken on the plane 4—4 of Figure 5, through the carbon holder feed screw;

Figure 5 is a fragmentary longitudinal sectional view taken on the plane 5—5 of Figure 3;

Figure 6 is a perspective elevational view of the positive carbon holders;

Figure 7 is a fragmentary end elevational view taken on the plane 7—7 of Figure 1; and

Figure 8 is a schematic wiring diagram of the holder shift actuating mechanism.

Reference is now made more specifically to the positive carbon holder assembly 10 illustrated in the accompanying drawings, and which assembly includes a base 12, positive carbon saddles 14 movably mounted on the base, carbon holder carriages 16 mounted on the saddles for movement transverse the direction of movement of the latter, carbon holders 18 carried by the carriages, and a carbon holder shift mechanism 20.

The positive carbon holder assembly 10 has been specifically designed to be utilized in the arc lamp presently manufactured under the trade name of Peerless Magnarc but it is to be understood that the carbon holder assembly may be utilized with other types of arc lamps with but minor changes in the construction of either the arc lamp housing or the carbon holder assembly.

As is conventional, the arc lamp includes a base frame 22 having a reflector 24 supported on one end thereof, and a negative carbon 26, supported by a negative carbon guide 28, axially of the reflector.

The positive carbon assembly base 12 includes a pair of end members 30 and 32 and a pair of relatively parallel L-shaped rails 34 and 36 connecting the end members. A saddle slide tube 38 is secured between the end members, adjacent one end thereof, and a feed screw 40 is rotatably journaled between the other ends of the end members. For reasons which will later become apparent as the following description proceeds,

the lands on the threads of the lead screw merge with the enlarged end 42 of the screw 40, the diameter of which enlarged end is equal to the major diameter of the lead screw.

A pair of carbon holder saddles 14 may be formed of a single casting and each includes a bridge plate 44 having a pair of lugs 46 and 48 on one end thereof, which lugs are connected by the transversely arcuate member 50 (see Figures 4 and 5). The lugs are each provided with aligned bores 52 whereby the lugs are slidably received on the crests of the threads on the lead screw 40. The other end of the bridge plates 44 are provided with yokes 54 which engage the saddle slide tube 33 whereby the saddles are guided for movement towards and away from the negative carbon 26. A shaft 56 is journaled in each of the members 50, transversely of the feed screw, and a clutch handle 48 is carried by the outwardly extending end of each of the shafts. A screw follower 60 is secured by fasteners 62 to the arm 64 on the shaft 58 for movement with the latter into and out of engagement with the threads on the lead screw 40. A coil spring 66 is disposed about the shaft 58 and terminally secured to the shaft and to the saddle to yieldingly bias the follower 60 into its thread engaging position. Obviously, the clutch handle 58 is movable to disconnect the saddle from the lead screw, and, as the lands of screw threads merge with the enlarged portion 42, the follower will ride upon the enlarged end and operatively disconnect the saddle from the lead screw.

The bridge plates 44 are each provided with an elongated guide slots 68, the sides of which guidingly engage the elongated block 70 which forms a part of the carbon holder carriage 16. The carriage also includes a carriage plate 72 which is secured to the upper face of the block and overlies the bridge plate 44, and a guide strap 74 which is secured to the undersurface of the block in sliding engagement with the undersurface of the bridge plate. A guide bar 76 is also secured to the undersurface of the block in parallel spaced relation to the edge of the guide strap adjacent the feed screw, to define a passage therewith for the reception of the carriage guide rail 78 which parallels the feed screw. A holder support arm 80 is secured to one end of the carriage plate and extends in parallel overlying relation to the latter, as is best shown in Figure 3. It will be noted that, as the saddles are advanced towards the negative carbon 26 by the feed screw 40, the carriages 16 are laterally guided by the rail 78. Obviously, when the rail is shifted laterally, the carriages will also be shifted laterally without interrupting the advancement of the saddles by the lead screw 40.

In order to maintain the guide rail 78 parallel to the feed screw 40, while laterally shifting the former, there is provided a first link 82 which is pivoted as at 84 to the end 30 of the base, the other end of the link 82 being connected by a pivot 86 to one end of the rail 78. A second link 88 is connected at one end by the pivot 90 to the other end of the rail 78, and the other end of the link 88 is pivoted to the L-shaped rail 34, as by pin 92. The overlapping intermediate portions of the links 82 and 88 are recessed as at 94 and 96 respectively and pivotally connected to each other by the pin 92. The ends of the links 82 and 88 which receive the pivot 86 and pin 92 respectively are slotted so as to permit a certain amount of lost motion between the links and their respective pivot pins. As is best shown in Figure 2,

an actuator arm 100 is attached to the guide rail 78 to laterally shift the latter. An L-shaped carbon guide support member 102 is secured to one end of the guide rail 78 and guidingly engages the end 32 of the base 12 as the member 102 is shifted with the guide rail. An adjustable stop 104 carried by the bracket 106 is provided to limit lateral movement of the guide rail and consequently limit shifting of the carriages 16. A lock nut 108 serves to retain the stop 104 in its adjusted position.

The carbon holders 13 each include a base plate 110 which is secured by fasteners 112 to the support arm 83 and electrically insulated therefrom in any desired manner. A standard 114 is carried by the base plate and has a notched upper end 116, L-shaped carbon support shoes 118 being disposed in the notches 116 and fastened therein by a set screw 120. A block 122 is carried by one end of each of the shoes 118, which block is provided with an upstanding longitudinally extending flange 124 which constitutes a seat for the positive carbon rods 126. A tube 128 is secured to the side of the block 122 and a clamp rod 130 is disposed in the tube, the upper end of which rod carries a clamp plate 132 which overlies the block 122. A collar 134 having circumferentially spaced apertures 136 in the periphery thereof is threadedly attached to the lower end 30 of the rod 130 and abuts the lower end of the sleeve to positively urge the clamp plate into engagement with the carbon rods 126 as the collar is rotated. A lever 138 is detachably receivable in the apertures 136 to facilitate rotating the collar. Conductors 140 are secured to one end of each of the shoes 118 as by clamp blocks 142 and fasteners 144, which conductors are otherwise connected to a suitable source of D. C. power in a conventional manner. A carbon support member 146 having a U-shaped seat 148 is provided on the holder 16 nearest the negative carbon 26 to support the carbon carried by the rearwardly disposed holder.

In order to insure proper registry of the positive carbons 126 with the negative carbon 26, there is provided a carbon guide member 150 which is provided with sidewise aligned U-shaped guide notches 152 and 154 in its upper end. As will be noted from a consideration of Figures 2 and 6, the carbon holders are relatively offset so that the carbon carried by the rearwardly disposed holder extends parallel to that carried by the forward holder and rests upon the support member carried by the forward holder. The notches 152 and 154 are spaced so that they will respectively guide the carbons carried by the forward and rear holders. The carbon guide 150 is vertically adjustably mounted by fasteners 156 in the carbon guide chute 158 which is secured to an insulative plate 160 carried by the carbon guide support member 102. As will be noted, the carbon guide 150 is insulated from the support member 102, and movable therewith as the latter is shifted with the guide rail 78.

A switch 162 is carried by the end 32 of the base 12 and has a switch arm 164 disposed in the path of movement of the resilient actuator finger 166 carried by the forward saddle 44. The switch 162 is electrically connected in series by conductor 168 with a second switch 170 carried by the end 30 of the base. The latter switch 170 is connected by conductor 172 to an alarm 174 which is otherwise connected by conductor 176 to a solenoid 178. The switch 162 is normally open and is closed by the finger 166 as the saddle 44 of

the forward carbon holder moves onto the enlarged end portion 42 of the feed screw to thereby operatively disconnect the forward carbon holder from the feed screw. The switch 170 is normally closed so that upon closing of the switch 162, the alarm 174 and solenoid 178 which is connected to the guide rail shift actuator arm 100 are energized to sound the alarm and shift the guide rail. This causes the carriage and the carbon holders carried thereby to also be shifted laterally of the path of travel of the saddles 14 to move the positive carbon carried by the forward holder out of operative registry with the negative carbon and to shift the carbon carried by the rear holder into registry therewith. Obviously, it is necessary to adjust the carbon carried by the rear holder so that the tip thereof is in transverse alignment with the burning end of the carbon carried by the forward holder at the time the carriage is shifted.

The second switch 170 is disposed in the path of movement of the guide rail 78 so as to be opened thereby when the rail reaches its shifted position. This will deactivate the alarm 174 and solenoid 178. Obviously, if for any reason the rail does not shift upon actuation of the solenoid, the alarm will continue to be sounded, thereby signaling the operator.

As is conventional, the feed screw 40 is driven through gears 180 and 182 which are respectively carried by the end of the feed screw and the shaft 184 which is operatively connected to a motor (not shown). The motor is preferably connected in multiple with the arc between the positive and negative carbons, and may be provided with a rheostat to permit variation in the speed of the motor. The motor and control mechanism therefor are well known, and form no part of this invention and accordingly, further description thereof is deemed unnecessary.

From the foregoing, it will be appreciated that there has been provided a carbon holder assembly by means of which a plurality of carbons may be successively disposed in proximity to a negative carbon without an appreciable time delay or break in the continuity of the arc light. Thus, short carbon rods may be positioned in the forward carbon holder to be completely consumed at which time the carriages are shifted by the solenoid to position the auxiliary carbon in operative registry with the negative carbon.

Having described the invention, what is claimed as new is:

1. In a carbon arc lamp including a negative carbon; a positive carbon assembly comprising a base, a first carbon holder mounted on said base for movement towards and away from the negative carbon, a second carbon holder mounted on said base between said first carbon holder and the negative carbon for movement parallel to the path of movement of said first carbon holder and so constructed and arranged to support a carbon in parallel spaced relation to the carbon carried by said first holder, common means for simultaneously advancing both of said holders towards said negative carbon, means responsive to a predetermined position of said second holder for operatively disconnecting said first holder from said advancing means, means for selectively shifting said carbon holders laterally of the path of movement thereof to simultaneously move the carbon carried by one of said holders out of registry with said negative carbon and move the carbon carried by the other of said holders into operative registry with the negative carbon.

2. In a carbon arc lamp including a negative carbon; a positive carbon assembly comprising a base, a first carbon holder mounted on said base for movement towards and away from the negative carbon, a second carbon holder mounted on said base between said first carbon holder and the negative carbon for movement parallel to the path of movement of said first carbon holder and so constructed and arranged to support a carbon in parallel spaced relation to the carbon carried by said first holder, common means for simultaneously advancing both of said holders towards said negative carbon, means responsive to a predetermined position of said second holder for operatively disconnecting said first holder from said advancing means, means for selectively shifting said carbon holders laterally of the path of movement thereof to simultaneously move the carbon carried by one of said holders out of registry with said negative carbon and move the carbon carried by the other of said holders into operative registry with the negative carbon, means responsive to a predetermined position of said second holder for automatically actuating said holder shifting means.
3. In a carbon arc lamp including a negative carbon; a positive carbon assembly comprising a base, a first carbon holder mounted on said base for movement towards and away from the negative carbon, a second carbon holder mounted on said base between said first carbon holder and the negative carbon for movement parallel to the path of movement of said first carbon holder and so constructed and arranged to support a carbon in parallel spaced relation to the carbon carried by said first holder, common means for simultaneously advancing both of said holders towards said negative carbon, means responsive to a predetermined position of said second holder for automatically actuating said holder shifting means.
4. In a carbon arc lamp including a negative carbon; a positive carbon assembly comprising a base, a first carbon holder mounted on said base for movement towards and away from the negative carbon, a second carbon holder mounted on said base between said first carbon holder and the negative carbon for movement parallel to the path of movement of said first carbon holder and so constructed and arranged to support a carbon in parallel spaced relation to the carbon carried by said first holder, common means for simultaneously advancing both of said holders towards said negative carbon, means responsive to a predetermined position of said second holder for operatively disconnecting said first holder from said advancing means, means for selectively shifting said carbon holders laterally of the path of movement thereof to simultaneously move the carbon carried by one of said holders out of registry with said negative carbon and move the carbon carried by the other of said holders into operative registry with the negative carbon, means responsive to a predetermined position of said second holder for automatically actuating said holder shifting means, a signal actuated in response to a predetermined position of said second holder, and means responsive to shifting of said holders for deactuating said signal and said holder shift actuating means.
5. In a carbon arc lamp including a negative carbon; a positive carbon assembly comprising a base, a first carbon holder mounted on said base for movement towards and away from the negative carbon, a second carbon holder mounted on said base between said first carbon holder and the negative carbon for movement parallel to the path of movement of said first carbon holder and so constructed and arranged to support a carbon in parallel spaced relation to the carbon carried by said first holder, common means for simultaneously advancing both of said holders towards said negative carbon, means responsive to a predetermined position of said second holder for operatively disconnecting said first holder from said advancing means, means for selectively shifting said carbon holders laterally of the path of movement thereof to simultaneously move the carbon carried by one of said holders out of registry with said negative carbon and move the carbon carried by the other of said holders into operative registry with the negative carbon.

holders into operative registry with the negative carbon, carbon guide means carried by said second carbon holder for guiding the carbon carried by said first carbon holder.

5. In a carbon arc lamp including a negative carbon; a positive carbon assembly comprising a base, a first carbon holder mounted on said base for movement towards and away from the negative carbon, a second carbon holder mounted on said base between said first carbon holder and the negative carbon for movement parallel to the path of movement of said first carbon holder and so constructed and arranged to support a carbon in parallel spaced relation to the carbon carried by said first holder, means for advancing said holder toward said negative carbon, a carbon guide mounted on said base for guiding the carbons carried by said first and second holders, and means for shifting said holders and carbon guides laterally of the path of movement of said holders to move the carbon carried by one of said holders out of operative registry with the negative carbon and move the carbon carried by the other holder into operative registry with the negative carbon.

6. In a carbon arc lamp including a negative carbon; a positive carbon assembly comprising a base, a first carbon holder mounted on said base for movement towards and away from the negative carbon, a second carbon holder mounted on said base between said first carbon holder and the negative carbon for movement parallel to the path of movement of said first carbon holder and so constructed and arranged to support a carbon in parallel spaced relation to the carbon carried by said first holder, means for advancing said holder toward said negative carbon, a carbon guide mounted on said base for guiding the carbons carried by said first and second holders, and means for shifting said holders and carbon guides laterally of the path of movement of said holders to move the carbon carried by one of said holders out of operative registry with the negative carbon and move the carbon carried by the other holder into operative registry with the negative carbon, a carbon support carried by said second carbon holder for guiding the carbon carried by said first carbon holder onto said carbon guide.

7. In a carbon arc lamp including a negative carbon; a positive carbon assembly comprising a base, an elongated carriage guide mounted on said base for movement relative thereto transverse the longitudinal axis of said guide, a first and a second positive carbon saddle slidably mounted on said base for movement parallel to said guide, means carried by said base for advancing said saddles towards said negative carbon, a carriage mounted on each saddle for movement transverse the direction of movement of said saddles, means slidably connecting said carriages to said carriage guide for movement therewith transverse the direction of movement of said saddles, means for shifting said carriage guide relative to said base to shift, and means responsive to a predetermined position of one of said saddles for operatively disconnecting that saddle from advancing means, a solenoid operatively connected to said carriage guide for laterally moving the same, and switch means for controlling actuation of said solenoid disposed in the path of movement, said one of said saddles to be closed in response to that saddle reaching said predetermined position.

8. In a carbon arc lamp including a negative

75

carbon; a positive carbon assembly comprising a base, an elongated carriage guide mounted on said base for movement relative thereto transverse the longitudinal axis of said guide, a first and a second positive carbon saddle slidably mounted on said base for movement parallel to said guide, means carried by said base for advancing said saddles towards said negative carbon, a carriage mounted on each saddle for movement transverse the direction of movement of said saddles, means slidably connecting said carriages to said carriage guide for movement therewith transverse the direction of movement of said saddles, means for shifting said carriage guide relative to said base to shift, and means responsive to a predetermined position of one of said saddles for operatively disconnecting that saddle from advancing means, a solenoid operatively connected to said carriage guide for laterally moving the same, and switch means for controlling actuation of said solenoid disposed in the path of movement, said one of said saddles to be closed in response to that saddle reaching said predetermined position, and signal means actuated by said switch means.

9. In a carbon arc lamp including a negative carbon; a positive carbon assembly comprising a base, an elongated carriage guide mounted on said base for movement relative thereto transverse the longitudinal axis of said guide, a first and a second positive carbon saddle slidably mounted on said base for movement parallel to said guide, means carried by said base for advancing said saddles towards said negative carbon, a carriage mounted on each saddle for movement transverse the direction of movement of said saddles, means slidably connecting said carriages to said carriage guide for movement therewith transverse the direction of movement of said saddles, means for shifting said carriage guide relative to said base to shift, and means responsive to a predetermined position of one of said saddles for operatively disconnecting that saddle from advancing means, a solenoid operatively connected to said carriage guide for laterally moving the same, and switch means for controlling actuation of said solenoid disposed in the path of movement, said one of said saddles to be closed in response to that saddle reaching said predetermined position, and signal means actuated by said switch means.

10. In a carbon arc lamp including a negative carbon; a positive carbon assembly comprising a base, an elongated carriage guide mounted on said base for movement relative thereto transverse the longitudinal axis of said guide, a first and a second positive carbon saddle slidably mounted on said base for movement parallel to said guide, means carried by said base for advancing said saddles towards said negative carbon, a carriage mounted on each saddle for movement transverse the direction of movement of said saddles, means slidably connecting said carriages to said carriage guide for movement therewith transverse the direction of movement of said saddles, means for shifting said carriage guide relative to said base to shift, and means responsive to a predetermined position of one of said saddles for operatively disconnecting that saddle from advancing means, a solenoid operatively connected to said carriage guide for laterally moving the same, and switch means for controlling actuation of said solenoid disposed in the path of movement, said one of said saddles

to be closed in response to that saddle reaching said predetermined position, means responsive to shifting of said carriage guide for deactuating said solenoid, and means for adjustably limiting shifting of said carriage guide.
